United States Patent Office.

ANDREW HARTMAN, OF CANTON, OHIO.

Letters Patent No. 65,079, dated May 28, 1867.

IMPROVED CAR-COUPING.

The Schedule referred to in these Letters Patent and making part of the same.

TO ALL WHOM IT MAY CONCERN:

Be it known that I, ANDREW HARTMAN, of Canton, in the county of Stark, and State of Ohio, have invented new and useful improvements in Car-Couplings; and I do hereby declare that the following is a full, clear, and exact description of my invention, reference being had to the accompanying drawings, forming a part of this specification, and to the letters of reference marked thereon, in which drawings—

Figure 1 is a sectional view of my improved car-coupling.

Figure 2 is a plan of the same; and

Figure 3 is an end view of the same.

The nature of my invention consists in the novel combination of a swinging-pin, sliding-block, and spring and catch, with the box of a coupling, so as to form a self-operating coupling; also in so constructing the swinging-pin as that when turned back its lower part shall form with the front of the box of the coupling a complete funnel-shaped mouth.

To enable others skilled in the art to make and use my invention, I will proceed to describe its construction and operation.

The coupling-box is made of the part A, bent in form shown in fig. 2, and the part B, which has the bolts b passing through the part A, thus firmly connecting them. The parts A and B are made of iron or steel, and the bolts b pass through suitably formed staples in the part B, as shown in fig. 1. The catch C is made as shown, the axes a a passing through the two sides of the part A, and the piece G projecting down through the hole d in the part B. The pin E Z D is of peculiar form, being composed of the pin proper E, the axial part Z, and the counterpoise or balance D, the whole forming a rotating pin rotating around the axis or bolt H, which passes through the two sides of the part A and the rotating pin E Z D, as shown. The block J has the pins O O in its sides, which pins pass through the slotted holes S S and project through the two sides of the part A of the coupling-box, thus supporting the block J and giving a means of sliding it from the outside of the coupling-box. The block J has the rod K at its rear end, which rod passes through the iron x, and has the spiral spring L around it and between the block J and iron x which keeps the block J pressed forward. In figs. 1, 2, and 3, the link F is shown as it appears when drawing the car. By raising the catch C by means of the handle I, which can be easily reached from the platform of the car, or by having a rod or cord attached, can be operated from the top of the car, the rotating pin E Z D takes the position E₂ Z D₂ and allows the link F to slip off over the end of the pin E, thus uncoupling the cars. When the link F is put in the position shown, by rotating the pin E Z D in the position E₁ Z D₁, the end of the pin E first forcing back the block J, which, as soon as said pin E passes the part T of the block, by the action of the spring L assumes its original position, thus securing the rotating pin in the position E₁ Z D₁, which holds the link in position F₁, as shown. The lip V on the block J prevents the rotating pin from turning too far and getting under the block J. The link being held in position E₁ in the coupling, and coming to a coupling with rotating pin in position E₁ Z D₁, causes said pin to rotate till the end of the pin E strikes the block J, the end of the link then sliding up on the pin E till it comes to the part T of the block J, when it causes said block to slide back, thus releasing the rotating pin, which assumes its original position, the pin E coming up into the link F, and the coupling of the cars is thus effected. When the swinging-pin is held by the block J in the position E₁ Z D₁, it is readily seen that the part D forms with the pieces A and B a funnel-shaped mouth, so that a link coming in any direction, whereby it would enter the mouth of the coupling, would be guided by the sides of this funnel-shaped mouth up over the pin E₁ and against the block J, and the coupling would be effected, as before shown.

Having thus fully described my invention, what I claim as new, and desire to secure by Letters Patent, is—

1. The peculiarly-shaped apron or balance D of the pin E Z D, so arranged and constructed as to act both as a balance and a part of the mouth of the coupling, substantially in the manner and for the purpose herein specified.

2. The peculiar combination and arrangement of the parts A and B, rotating pin E Z D, bolt H, block J, spring L, iron K, pins O O, slots S S, catch C with handle I, the several parts being arranged as hereinbefore shown, and the whole forming a self-acting coupling, operating substantially in the manner specified.

As evidence that I claim the foregoing I have hereunto set my hand in presence of two witnesses.

ANDREW HARTMAN.
